UNITED STATES PATENT OFFICE.

SAMUEL D. WASHBURN, OF DORCHESTER, MASSACHUSETTS.

MACHINE FOR MAKING PAPER CUPS.

1,266,644.

Specification of Letters Patent. Patented May 21, 1918.

Application filed March 15, 1911. Serial No. 614,581.

To all whom it may concern:

Be it known that I, SAMUEL D. WASHBURN, a citizen of the United States, and residing at Dorchester, county of Suffolk, 5 State of Massachusetts, have invented an Improvement in Machines for Making Paper Cups, of which the following description, in connection with the accompanying drawing, is a specification, like characters 10 on the drawing representing like parts.

This invention provides a machine for forming drinking cups or similar articles from paper. There is a large increasing demand for vessels, and particularly drinking 15 cups, adapted for temporary and individual use and of such low cost that they may be thrown away or destroyed after a single use. This is particularly true of drinking cups, and in the disclosure of the 20 present invention the term "cup" will be used, although it is to be understood that any hollow vessel adapted to be made by the machine of the invention is within the scope thereof.

It is essential to a satisfactory cup that it shall be so made as to have a well defined shape and one that will be maintained during its use; that it shall not present sharp or irregular edges injurious or uncomfortable to the user; and that it shall be 30 as cheap as possible.

The machine of the present invention is devised to form cups having the foregoing requirements from a paper blank in an exceedingly expeditious manner. The cups thus formed have the further advantage that they need not be formed until required for use and, hence, a minimum amount of space is occupied and the hygienic condition of 40 the cups is assured. The paper may be kept in a solid, compact roll occupying little space and easily shipped to the points where the cups are to be made, while the form of the roll enables it to be protected 45 from contamination so that the cups may be formed directly from clean uncontaminated paper.

Another advantage of the invention resides in the fact that the cups may be made 50 by the user, thus doing away with all the expense attendant upon the manufacture of the cups in a factory and their delivery to the user.

In the formation of the cups three dies 55 are used, one being a hollow die with a cylindrical edge, the second being a plunger

die adapted to fit within the hollow die, and the third being a plunger fitting concentrically over the main plunger die and adapted to turn over the edge of the cup 60 and throw it back upon the body thereof. The combination of these three dies to effect this result is believed to be new, and the invention is, therefore, not limited to the particular mechanical devices for securing 65 the relative movement of the dies in the formation of the cup.

The invention also provides means for causing the vertical or side walls of the cup to present a series of symmetrically-disposed box plaits, and the entire edge of the cup to present an annular downturned portion so that the folds of the plaits are locked whereby it is impossible to destroy the shape of the cup by releasing the folds 70 without a determined effort which breaks the paper. The disposition of the paper into these folds in the side walls and turned edge gives the cup a very substantial and solid form so that it readily maintains its 75 shape under use, and can be easily handled and placed on a table when empty or when filled with liquid.

The invention in its more specific form contains a number of mechanical features 80 and these will be described more in detail in the specification.

The invention is particularly designed for producing a paper cup or article such as is made the subject of my Patent No. 90 1,065,486, granted June 24, 1913, for paper drinking cup.

The nature of the invention will, in fact, appear more fully in the accompanying description and drawings and will be particularly defined in the appended claims.

The drawings represent a machine embodying the invention and adapted for installation in any place where it is desired to make use of drinking cups.

In the drawings Figure 1 is a front elevation of the machine with the front of the casing removed to show the mechanism;

Fig. 2 is a plan view of the actuator or handle by which the parts of the device are 105 operated;

Fig. 3 is a vertical central cross section of the construction shown in Fig. 2;

Fig. 4 is a side elevation partially in cross section of the construction shown in 110 Fig. 1;

Fig. 5 is a detail showing the track for

a stud on the lower end of a rack bar to be described;

Fig. 6 is a plan view of the lower portion of the device looking down from beneath the plunger dies;

Fig. 7 is a detail in vertical cross section showing the lower hollow die and the bed plate;

Fig. 8 is an enlarged side elevation partially in cross section of the end of the dies;

Fig. 9 is a plan of a portion of the strip of paper from which the cups are formed;

Fig. 10 is a view looking down into one of the cups partially formed;

Fig. 11 is a side elevation of the completed cup.

The chief feature of the invention resides in the three dies and the means for giving relative movement to these dies whereby the cup is formed with its edge turned over.

The particular mechanism for securing the proper relative movements of the dies and the particular position of the dies is not essential but it is desirable that the hollow die shall be mounted on a vertical axis and that the plunger dies shall be mounted vertically above the hollow die and have their movement toward and from the hollow die, and the construction is thus illustrated.

It is also very important that the lines along which the paper shall fold as it takes the conical form between the dies shall be defined at the beginning of the operation. Otherwise the cup may be formed in a very irregular and unsatisfactory manner. An important feature of the invention lies in the means for defining the lines of fold of the cup.

In order that the cups may be formed expeditiously and by unskilled persons it is desirable that there shall be combined with the forming dies means for positioning the blank between the dies at the proper time and when, as is preferred, a continuous strip of paper is used that means shall be provided for severing the blank from the strip.

Preferred forms of mechanism for these purposes are herein disclosed and these mechanisms are so arranged that the entire apparatus is operated to form the cup complete without other attention than the single movement of an actuator. Such an actuator in the form illustrated is shown as a crank handle, and the construction is such that when a person grasps the crank handle and gives it a turn the blank will be fed between the plungers, severed from the end of the sheet, the plunger will be operated and the cup formed, and the various mechanisms returned to their original position.

Taking up now the construction illustrated in detail, the parts are shown as inclosed by a box or casing having the side walls 2 and the rear wall 3. The front of the casing is

not shown, and may take any desirable form and may be closed save at a point opposite the space between the dies to enable the cup to be removed from the casing.

Near the lower portion of the casing a table or bed plate 4 is mounted and this bed plate is provided with a central aperture over which the paper blank for the cup to be formed is fed. This central aperture is beveled downwardly as indicated at 5 about its periphery except at certain symmetrically-arranged points 6 (herein shown as four in number) where it is not beveled, thus leaving fingers or points. It will thus be seen that the flat paper blank is supported by the bed plate between the open dies over the opening and when the paper blank is depressed through this central opening the fingers 6 for initiating the lines of fold will insure the cup being formed with symmetrical folds. The symmetrically-disposed box plait which are initiated by the fingers 6 give the substantial and solid form to the cup desired, and when the edge of the cup is downturned, these folds are so locked that it is impossible to destroy the shape of the cup by releasing the folds without a determined effort.

The hollow die is located centrally beneath the aperture in the bed plate 4 and is shown at 7 supported on a brace 8 extending between the side walls of the casing. The interior of the hollow die takes the general form of the exterior of the cup to be formed and this die has an upper free edge 9 cylindrical in form, and the term "cylindrical" is used in a broad form—not limited to circular, although the circular form is preferred. This edge is as thin as may be and yet possess sufficient strength.

The co-operating plunger dies are mounted vertically above the hollow die and in the form shown the plunger dies are moved toward and from the hollow die, the hollow die being fixed in position.

The main plunger die 10 has the general shape of the interior of the hollow die and of the interior of the cup to be formed, and preferably is provided on its lower face with a slightly roughened or other suitable surface to prevent the paper from slipping beneath it. This plunger die 10 has projecting upwardly therefrom a bar 12 and this bar is guided vertically in the end of a bracket 130 projecting from the rear wall 3 of the casing.

The other plunger die 14 is arranged concentrically of the die 10 and consists simply of an annular shell of sufficient diameter to slide over the exterior of the hollow die 7 without cutting or injuring the paper of the cup which is forced in between. This die 14 is interiorly beveled at its lower edge as shown at 15 to prevent it cutting or tearing the paper as it comes down to turn the edge 130

of the cup over. This die 14 is carried by two rods 16 connected at their lower ends to lugs 17 projecting from the die and at their upper ends by a strut 18 sliding over the end 5 of the bar 12.

The movement of the plunger dies to and from the hollow die is secured in the form illustrated by a rack and gear and weight mechanisms. 19 is a horizontal shaft extending through the side walls of the casing and carrying a wide gear 20. The bar 12 is provided on its front face with a rack 13 adapted to mesh with the left hand side of the gear 20. The strut 18 has depending therefrom a bar 21, likewise provided on its front face with a rack 22 adapted to mesh with the right hand side of the gear 20. A pin 23 projects from the bar 12 over the strut 18. A flexible connection 24 is connected to the strut 18 and extends over pulleys 25 and 26 and has attached to its lower end a weight 27. An arm 28 projects up from the bracket 130 and is provided with an anti-friction roll 29 opposite the center of the gear 20, this anti-friction roll running against the back 25 of the bar 12.

It will be seen, therefore, that when the shaft 19 is turned the gear 20 intermeshing with the rack 12 will depress the plunger die 10 into co-operative engagement with the hollow die 7. During this movement by reason of the stud 23 the concentric plunger die 14 will be carried downwardly along with the die 10 but will have no action upon the paper. Upon the completion of the downward movement of the die 10 the rack 20 will then engage the rack 22 and immediately depress the die 14. As the die 10 comes down it strikes the blank of paper resting over the aperture in the bed plate 4 and depresses it into the hollow die, the fingers 6 defining the lines of fold of the paper so that as the paper goes down into the hollow die it takes the form shown in Fig. 10, 40 and as the die 10 reaches its lowermost position the paper is firmly pressed into shape between it and the hollow die and stands in a generally conical form projecting upwardly. The die 14 then comes into action 45 passing down inside of the cone of paper and turning the upper edge of the paper back over the edge 9 of the hollow die and back upon itself, the bevel 15 preventing the tearing or cutting of the paper, and the folded condition of the paper enabling it to be turned back. The cup when finally formed 50 presents the condition shown in Fig. 11 and when a reasonable amount of pressure is used the paper will maintain its compact 55 folded condition.

A great advantage of this cup lies in the fact that no cement, glue, or other material is used other than the paper itself, and that the paper is not handled from the time it is 60 placed in the machine until the time the cup

is taken out by the user. The series of symmetrically-disposed box plaits into which the side walls of the cup are formed and pressed are also of great advantage in strengthening the cup and enabling it to be 65 locked in its shape as already pointed out. The folding back of the upper edge of the cup causes the edge of the completed cup to be smooth, and at the same time prevents the unfolding of the cup and enables it to be 70 filled with water or other material and hold its shape.

The blanks of paper from which the cups are formed are preferably circular in shape and when an automatic feed is to be used 75 are preferably united into one long strip, a portion of which is shown in Fig. 9 where 30 represents one complete blank and 31 and 32 portions of the adjacent connected blanks. The strip of paper is wound up into a roll 80 33 and mounted in the lower portion of the casing upon a shaft 34, a pin 35 serving to lock the shaft removably in place.

The strip of paper passes up between feeding rolls 36 and 37 to the top of the bed 85 plate and is fed by these rolls along the top of the bed plate over the central aperture therein and positioned thereover by the gage 38 which is shown as a semi-annular rib projecting up from the top of the bed plate. 90 With the blanks in the circular form as they come against these ribs 38 they will be centered properly over the hollow die.

As a suitable means for operating the feeding mechanism the upper roll 37 is 95 shown as resting upon the lower roll 36, and the lower roll 36 is shown as positively operated, a gear 39 being mounted upon the shaft of the lower roll and co-operating with a rack bar 40. This rack bar extends vertically 100 and is guided in a bracket 41 projecting from the side wall of the casing, and has free play in the bracket in the plane of the gear 39. At its lower end it is provided with a stud 42 sliding in a cam groove 43 of 105 the general shape shown in Fig. 5. This cam groove is formed in a block 45 attached to the side wall of the casing, and has one vertical straight portion united by a curve at its lower end with an inclined portion. 110 The straight and inclined portions connect at their upper ends where a spring switch 44 is located which normally occupies the position shown in Fig. 5 and directs the stud 42 down the vertical portion of the cam groove and allows it upon its upper movement to slide from the inclined portion back into the vertical portion.

The rack bar 40 at its upper end is provided with anti-friction rolls 46 and an apertured head 47. A lever 48 fulcrumed at 49 to the side wall of the casing extends between the anti-friction rolls 46 and is held normally elevated by the spring 50. A spring 51 surrounds the lever 48 and presses

at one end against the apertured head 47 and at the other end against a collar 52 secured to the lever. A wiper cam 53 is carried by the shaft 19 and actuates the said lever 48.

The operation of the feeding mechanism will now be apparent. As the wiper cam strikes the lever 48 its end is depressed against the action of the spring 50, thus carrying down the rack bar 40 with the stud 42 sliding down in the straight portion of the cam groove 43 and the actuation of the gear 39 on the feeding roll is consequently caused. When the stud 42 reaches the lower portion of the cam groove 43 the spring 51 forces the lower end of the rack bar to the left, looking at Figs. 4 and 5, and the stud 42 slides up in the inclined portion of the cam groove, the spring 50 turning the rack bar upwardly, and when the stud 42 reaches the upper end of the inclined portion of the cam groove it moves the switch 44 aside and continues on up. The result is that the feed rolls are not actuated during the upward movement of the rack bar.

It is necessary in using the strip of paper to sever the blank to be formed into the cup from the strip, and for this purpose suitable cutting mechanism is provided. In the form shown, the bed plate is slotted at 54 and a knife 55 is mounted above the slot. This knife is fulcrumed at 56 and provided with a spring 57 tending to hold it normally elevated. At its opposite end it carries a projection 58 in the path of a projection 59 from the rack bar 40. The parts are so timed that when the rack bar 40 is depressed and the strip is fed to bring the blank against the gage 38 the knife descends and 40 severs the strip along the line 60.

It will be seen that the mechanisms for feeding the blank into position, for severing the blank from the strip, and for forming the cup all receive their actuation when the shaft 19 is rotated in one direction, and that when their operations are completed the weight 27 and the spring 50 act to restore the mechanisms to normal position ready for the next operation. In order to actuate the shaft 19 a suitable actuator is provided and in the form shown comprises a crank 61. If the crank were connected directly to the shaft it would, after having been operated to feed and sever the blank and form the 55 cup, fly back into its original position when released. It is desirable to provide a form of actuator which may always be moved in the same direction, which will always be left in the same position, and which will be incapable of being actuated farther than necessary to secure the complete formation of the cup.

To secure these results the construction illustrated in detail in Figs. 2 and 3 is provided. In this construction the crank 61 is

provided with a two-part clutch head, one part 62 being secured by the pin 63 to the shaft 19 and the other part 64 being integral with the arm of the crank. The opposing surfaces of these heads have coöperating 70 cam faces, as illustrated. The part 64 of the head slides freely on the shaft 19 and is normally pressed toward the part 63 by the coiled spring 65. This spring is inclosed in the part 64 by a thimble 66 which bears 75 against a pin 67 secured in the shaft 19. A cam faced hub 68 is secured by screws 69 to the side wall of the casing concentrically to the part 62, and a rib 70 projecting from the part 64 coöperates with the cam face on 80 the hub 68. This cam face is so shaped that during the movement of the crank 61 to secure the operation of the various mechanisms the clutch faces of the parts 62 and 64 are in engagement, but as soon as this movement ceases the cam face coöperating with the rib 70 forces the clutch members apart, and they do not again come into engagement until the handle is in position to secure the next operation. This allows the mechanisms 85 to be returned to their normal positions by the spring and the weight without in any way affecting the operation of the handle or causing it to be reversely rotated.

Having fully described my invention 95 what I claim as new and desire to secure by Letters Patent is:

1. A machine for forming cups from paper comprising a hollow cylindrical edged die, a pair of concentrically-arranged 100 plunger dies adapted to fit respectively within and over said hollow die, means for giving relative movement to said dies first to cause the inner plunger die and hollow die to coöperate to shape the paper blank 105 into cup form and next to cause the outer plunger die to coöperate with the hollow die to turn the edge of the cup over, and means for initiating symmetrically the lines of fold of the blank as the said dies act 110 thereon so as to form a series of diametrically-disposed box-plaits.

2. A machine for forming cups from paper comprising a hollow cylindrical edged die, a pair of concentrically-arranged 115 plunger dies adapted to fit respectively within and over said hollow die, means for supporting a flat paper blank between the said hollow die and the said pair of plunger dies when the dies are in open position, means for giving relative movement to said dies first to cause the inner plunger die and hollow die to coöperate to shape the paper blank into cup form and next to cause the outer plunger die to coöperate with the hollow die to turn the edge of the cup over, and means for feeding the blank into position 120 between the dies.

3. A machine for forming cups from paper comprising a hollow cylindrical edged 130

die, a pair of concentrically-arranged plunger dies adapted to fit respectively within and over said hollow die, means for giving relative movement to said dies first to cause the inner plunger die and hollow die to coöperate to shape the paper blank into cup form and next to cause the outer plunger die to coöperate with the hollow die to turn the edge of the cup over, means for feeding the blank into position between the dies, and means for initiating symmetrically the lines of fold of the blank as the said dies act thereon, so as to form a series of symmetrically-disposed box-plaits.

15 4. A machine for forming cups from paper comprising a hollow cylindrical edged die, a pair of concentrically-arranged plunger dies adapted to fit respectively within and over said hollow die, means for supporting a flat paper blank between the said hollow die and the said pair of plunger dies when the dies are in open position, means for giving relative movement to said dies first to cause the inner plunger die and hollow die to coöperate to shape the paper blank into cup form and next to cause the outer plunger die to coöperate with the hollow die to turn the edge of the cup over, an actuator, connections between said dies and said actuator whereby upon the actuation of the said actuator the coöoperative movements of the several dies are secured to form the cup, and mechanism acting thereupon to release the dies to permit them to return to open position.

5. A machine for forming cups from paper comprising a hollow cylindrical edged die, a pair of concentrically-arranged plunger dies adapted to fit respectively within and over said hollow die, means for giving relative movement to said dies first to cause the inner plunger die and hollow die to coöperate to shape the paper blank into cup form and next to cause the outer plunger die to coöperate with the hollow die to turn the edge of the cup over, an actuator, connections between said dies and said actuator whereby upon the actuation of said actuator the coöoperative movements of the several dies are secured to form the cup and the dies are then released to return to open position, and means for preventing movement of the actuator upon the return of the dies to open position.

6. A machine for forming cups from paper comprising a hollow cylindrical edged die, a pair of concentrically-arranged plunger dies adapted to fit respectively within and over said hollow die, means for giving relative movement to said dies first to cause the inner plunger die and hollow die to coöperate to shape the paper blank into cup form and next to cause the outer plunger die to coöperate with the hollow die to turn the edge of the cup over,

means for feeding the end of a strip of paper into position between the dies, and means for severing a blank from the end of the strip when in position.

7. A machine for forming cups from paper comprising a hollow cylindrical edged die, a reciprocating plunger die adapted to fit within the hollow die and form the cup from the blank, a reciprocating cylindrical plunger die mounted concentrically of said first die and adapted to pass over the hollow die to turn the edge of the cup over upon itself, means for supporting a flat paper blank between the said hollow die and the said pair of plunger dies when the dies are in open position, means for bringing said plunger dies into operation successively in connection with said hollow die, and separate means for restoring said plunger dies to open position upon the completion of the movement of the cylindrical plunger die.

8. A machine for forming cups from paper comprising a hollow cylindrical edged die, a reciprocating plunger die adapted to fit within the hollow die and form the cup from the blank, a reciprocating cylindrical plunger die mounted concentrically of said first die and adapted to pass over the hollow die to turn the edge of the cup over upon itself, means for bringing said plunger dies into operation successively in connection with said hollow die, feeding devices to feed the end of a strip of paper into position between the dies, cutting mechanism to sever a blank from the end of the strip, an actuator and connections therefrom to said dies, feeding devices, and cutting mechanism whereby upon a single movement of said actuator the feeding mechanism, cutting mechanism, and dies are operated in proper sequence.

9. A machine for forming cups from paper comprising a hollow cylindrical edged die, a reciprocating inner plunger adapted to fit within the hollow die and form the cup from the blank, a reciprocating outer cylindrical plunger die mounted concentrically of said inner die and adapted to pass over the hollow die to turn the edge of the cup over upon itself, a rack bar connected to the inner plunger die, a second rack bar connected to the outer plunger die and having its teeth continuing above the teeth of the first rack bar, a connection between said rack bars causing downward movement of the first to be transmitted to the second but permitting downward movement of the second independently of the first, and a gear having its teeth arranged to mesh with the teeth of both rack bars whereby upon rotation of the gear the inner plunger die will first be moved into coöperation with the hollow die and next the outer plunger die will be moved into coöperation with the hollow die.

10. A machine for forming cups from paper comprising a hollow cylindrical edged die, a reciprocating inner plunger die adapted to fit within the hollow die and 5 form the cup from the blank, a reciprocating outer cylindrical plunger die mounted concentrically of said inner die and adapted to pass over the hollow die to turn the edge of the cup over upon itself, a rack bar connected to the inner plunger die, a second rack bar connected to the outer plunger die and having its teeth continuing above the teeth of the first rack bar, a connection between said rack bars causing downward movement 10 of the first to be transmitted to the second but permitting downward movement of the second independently of the first, and a gear having its teeth arranged to mesh with the teeth of both rack bars whereby upon rotation of the gear the inner plunger die will first be moved into coöperation with the hollow die and next the outer plunger die will be moved into coöperation with the hollow die and means for restoring both plunger 20 dies to open position.

11. A machine for forming cups from paper comprising a hollow cylindrical edged die, a pair of concentrically-arranged plunger dies adapted to fit respectively within 30 and over said hollow die, the outer plunger die having an interior bevel at its lower edge, means for supporting a flat paper blank between the said hollow die and the said pair of plunger dies when the dies are 35 in open position, and means for giving relative movement to said dies first to cause the inner plunger die and hollow die to coöperate to shape the paper blank into cup form and next to cause the outer plunger die to 40 coöperate with the hollow die to turn the edge of the cup over.

12. A machine for forming cups from paper comprising a hollow cylindrical edged die, a pair of concentrically-arranged plunger dies adapted to fit respectively within 45 and over said hollow die, the outer plunger die having an interior bevel at its lower edge, and means for giving relative movement to said dies first to cause the inner 50 plunger die and hollow die to coöperate to

shape the paper blank into cup form and next to cause the outer plunger die to coöperate with the hollow die to turn the edge of the cup over, and means for initiating symmetrically the lines of fold of the blank 55 as the said dies act thereon so as to form a series of symmetrically disposed box plaits.

13. A machine for forming cups from paper comprising a hollow cylindrical edged die, a pair of concentrically-arranged plunger dies adapted to fit respectively within and over said hollow die, means for giving relative movement to said dies first to cause the inner plunger die and hollow die to coöperate to shape the paper blank into cup form 65 and next to cause the outer plunger die to coöperate with the hollow die to turn the edge of the cup over, a bed plate to support the paper blank and an aperture to permit the passage of the dies, a plurality of symmetrically-arranged projecting points at the 70 edge of said aperture for engaging symmetrically the lines of fold of the blank as the said dies act thereon so as to form a series of symmetrically disposed box plaits. 75

14. A machine for forming cups from paper comprising a hollow cylindrical edged die, a pair of concentrically-arranged plunger dies adapted to fit respectively within and over said hollow die, means for giving 80 relative movement to said dies first to cause the inner plunger die and hollow die to coöperate to shape the paper blank into cup form and next to cause the outer plunger die to coöperate with the hollow die to turn the 85 edge of the cup over, a bed plate to support a flat paper blank between the said hollow die and the said pair of plunger dies when the dies are in open position, an aperture to permit the passage of the dies, and positioning means to position a circular blank 90 concentrically with said aperture.

In testimony whereof, I have signed my name to this specification, in the presence of two subscribing witnesses.

SAMUEL D. WASHBURN.

Correction in Letters Patent No. 1,266,644.

It is hereby certified that in Letters Patent No. 1,266,644, granted May 21, 1918, upon the application of Samuel D. Washburn, of Dorchester, Massachusetts, for an improvement in "Machines for Making Paper Cups," an error appears in the printed specification requiring correction as follows: Page 4, lines 111-112, claim 1, for the compound word "diametrically-disposed" read *symmetrically-disposed*; and that the said Letters Patent should be read with this correction therein that the same may conform to the record of the case in the Patent Office.

Signed and sealed this 18th day of June, A. D., 1918.

[SEAL.]

F. W. H. CLAY,

Acting Commissioner of Patents.
